UNITED STATES PATENT OFFICE

155,433

DESIGN FOR A PLASTIC FILM MATERIAL

Robert P. Magid, Forest Hills, N. Y., assignor to
Hartford Textile Corporation, New York, N. Y.,
a corporation of New York

Application March 8, 1948, Serial No. 144,979

Term of patent 3½ years

(Cl. D92—1)

To all whom it may concern:

Be it known that I, Robert P. Magid, a citizen of the United States, residing at Forest Hills, in the county of Queens and State of New York, have invented a new, original, and ornamental Design for a Plastic Film Material, of which the following is a specification, reference being had to the accompanying drawing, forming part thereof.

The figure is a plan view of one design unit of my plastic film material, showing my new design. Said design unit is repeated over the plastic film material, as indicated by the line extension beyond the design unit.

I claim:

The ornamental design for a plastic film material, substantially as shown and described.

ROBERT P. MAGID.
